UNITED STATES PATENT OFFICE.

WILLIAM KOCH, OF NEW YORK, N. Y., ASSIGNOR TO THE KRUSE CHECK AND ADDING MACHINE COMPANY, OF NEW YORK.

CASH-REGISTER.

SPECIFICATION forming part of Letters Patent No. 140,108, dated November 4, 1890.

Original application filed September 3, 1888, Serial No. 284,450. Divided and this application filed February 27, 1890. Serial No. 342,004. (No model.)

To all whom it may concern:

Be it known that I, WILLIAM KOCH, of the city, county, and State of New York, have invented certain new and useful Improvements 5 in Cash-Registers and other Similar Machines; and I do hereby declare that the following is a full and exact description thereof, reference being had to the accompanying drawings, and to the letters of reference marked 10 thereon, making a part of this specification.

My invention relates to an improvement in devices for governing a train of adding-wheels, and has for its object to prevent an independent movement of either of the adding-wheels out of its proper order—that is to say, a movement of any one of the adding-wheels in advance of that to the left of it—and to provide for the automatic movement 15 of the wheels in succession after their actuating-pawl have all been carried into position for action.

It consists in the combination and arrangement of devices for the purpose hereinafter described and claimed.

25 In the accompanying drawings, Figure 1 is a side elevation, partly in section, of the adding mechanism in a cash indicating and adding machine, constructed as described in my pending application for Letters Patent, Serial 30 No. 284,450, dated September 3, 1888. Fig. 2 is a similar view illustrating the pawl actuating one of the adding-wheels when retracted. Fig. 3 is a transverse section in the line $x-x$ of Fig. 1. Fig. 4 is an elevation from the 35 front, at line $y-y$ of Fig. 1, of the master-wheels, to which the adding-wheels are geared, and of the type-segments by which said wheels are moved, the adding-wheels and intermediate gear, the locking-dogs, and the 40 movements actuating the type-segments being omitted from the view. Fig. 5 is a sectional elevation similar to Fig. 1, taken in the line $z-z$ of Fig. 6, illustrating a modification of my invention; Fig. 6, a detail plan 45 view of the master adding-wheels and their locking-pawl, shown in Fig. 5.

Similar letters indicate like parts in all of the figures.

50 A represents the adding-wheels indicating, respectively, units, tens, hundreds, and

thousands in a train geared together in the usual manner, so that each wheel shall move one step at every complete revolution of that next to the left thereof and yet admit of being revolved independently of said wheel on 55 the left, only one of said wheels being shown. These adding-wheels are shown as mounted in a cash-recording machine constructed as described in my pending application for Letters Patent, of September 3, 1888, Serial No. 60 284,450, the present application being filed as a division thereof.

B represents a series of type-bearing segments oscillating upon a fixed shaft C to swing severally under an opening D in the casing 65 of the machine or in the plate of a suitable printing apparatus, and E E E are the keys or stops mounted to radiate from the axis of each type-segment in position to arrest severally by their depression the movement of 70 the underlying segment, whereby when either key is depressed the type on the segment corresponding with that key will be arrested at the opening D to serve as an indicator or for use in producing an imprint upon the recording-strip. 75

The adding-wheels A are mounted to be read at the front of the machine, and are severally actuated each by a toothed master-wheel F, meditately geared to a pinion G on 80 the hub of the actuating-wheel.

The master-wheels F F are mounted to turn loosely upon an extension of the fixed shaft C, upon which the type-segments B B oscillate, and are each engaged and moved, 85 as required, by a spring-actuated pawl H, pivoted upon an arm I, projecting from a cam wheel or disk J, revolving loosely upon said shaft C at the right of each master-wheel and in close proximity thereto. 90

Each pawl-arm I is actuated by a spring L, which is brought into play by the retraction of said arm against the stress of the spring, and the pawl H thereon, sliding freely over the teeth of the master-wheel as the arm 95 moves back, will engage the same upon its return and thereby move the master-wheel and with it the adding-wheel.

Each adding-wheel A is represented by a corresponding type-bearing segment B, bear- 100

ing the same set of numbers, and by a corresponding series of keys or stops E E controlling the segment, and severally designated by numbers corresponding with the type and 5 with the numbers on said wheel. Each type-segment is coupled by a connecting-rod K or other equivalent device with the swinging arm I, carrying the pawl H, which engages the master-wheel F, by which the adding-wheel A appropriate to said segment is actuated.

The movement of either of the type-segments toward its governing stops or keys E E, whereby one of the types upon the segment 15 is brought to the opening D, will thus operate to swing back the pawl H actuated thereby far enough to cause the pawl to move upon its return the master-wheel which it engages, and consequently the adding-wheel 20 geared thereto, a proportionate distance.

An independent movement of either of the adding-wheels out of its proper order—that is to say, an independent movement of any 25 adding-wheel in advance of that to the left of it—is prevented by introducing in the train by which the master-wheel F is geared to its appropriate adding-wheel a spur-wheel M, having a wider face than said master-wheel, and pivoting a locking-dog N in position to 30 be carried into engagement with the teeth of said spur-wheel M. This dog is automatically withdrawn from the wheel M by means of a spring O, and is carried toward it by contact with the cam projection on the 35 periphery of the cam wheel or disk J, which carries the pawl actuating the master-wheel next to the left of that locked by the dog, said cam projection being so located and proportioned in length as that the dog will be moved 40 thereby so soon as the retraction of the pawl begins, and will be thereby held in engagement with the spur-wheel, so as to lock the adding-wheel until the pawl has fully completed its stroke and returned to its first or 45 normal position. Hence no one adding-wheel can be moved after either of the pawls actuating the adding-wheels on the left thereof has been retracted until said pawl and the adding-wheel actuated thereby have completed 50 their movement.

If the construction of the machine be so far modified as to permit the adding-wheels A to be brought into close proximity to the pawl-actuated master-wheel F, as shown in Fig. 5, 55 so as to render the intervention of a spur-wheel M in the train unnecessary, each locking-dog N, actuated by a cam moving in unison with the pawl H, actuating a master-wheel, may be made to engage directly the 60 master-wheel next to the right, as shown in Fig. 6. In such case the pivoted arm carrying the dog N is actuated by a lever P, projecting radially from the pivoted hub of said arm, and bent at its outer end to bear against 65 the periphery of the cam-disk J, moving with the arm carrying the pawl H, actuating the master-wheel next to the left, the dog being

adapted when the cam-disk J has forced outward said lever P to engage the teeth of the master-wheel on the right and lock it. The 70 reverse movement of either wheel is prevented in the customary manner by a spring-actuated pawl R. (See Fig. 5.)

In the operation of the device the pawls H H are first retracted by the movement of the 75 several type-segments as they are turned against such of the stops E E as have been previously depressed to determine the type to be brought to line of view or print at the opening D. So soon as the movement of each 80 pawl H begins, the dog N, resting in the recess in the periphery of the cam-disk J, to which the arm I, carrying the pawl, is secured, is carried out of said recess, and the opposite face of the dog is thereby forced, against the 85 stress of the spring actuating the dog, into engagement with the teeth of the master-wheel F, thereby locking it and the adding-wheel 90 geared thereto. In the retraction of each pawl its spring L is brought under stress, and so soon as the pawl is released the spring operates to carry it back to its first or normal 95 position. The pawls are all simultaneously released when the type-segments are thrown back to their first position; but the first pawl 100 at one will be free to move because of the lock upon the wheels actuated by each of the others through the engagement of the dogs therewith, in manner as described. Upon the return of the first pawl to its first position 105 under the influence of the spring L the dog riding upon the cam-disk to which the arm carrying said pawl is secured is permitted to drop back under the influence of its spring O 110 into the recess in said disk, and thus free the master-wheel engaged thereby. When this wheel is free to move, the pawl actuating the same will operate under the influence of the spring L to drive it, and when the movement of the pawl is completed the next dog 115 will be in turn released, and so on, the several dogs being successively moved and the several adding-wheels left free to be automatically actuated by the pawls in regular succession, each after the movement of the first pawl actuating the wheels to the right is completed.

It is evident that the automatic successive movement of the several adding-wheels in regular order is obtained by the devices herein 120 described independently of the mechanism by which a retraction of the actuating-pawls H H is effected, and that said devices may be employed with any form of apparatus in 125 which adding mechanism is required and wherein provision is made for moving a series of pawls H H. My invention is not therefore limited to the combination of the adding-wheels and their actuating-pawls and locking mechanism, substantially as described, with 130 the type-segments in the cash indicating or recording machine, as described, but is applicable to various forms of apparatus which it is not necessary herein to enumerate.

What is claimed is—

1. The combination, with a train of adding-wheels and the oscillating pawl by which each adding-wheel is meditately actuated, of a cam moving with the pawl and a dog actuated by said cam and made thereby to lock the next adding-wheel during the movement of said pawl, substantially in the manner and for the purpose herein set forth. 5
2. The combination of a train of adding-wheels, pawls severally actuating said adding-wheels, a spring actuating each pawl and brought into play by the retraction of said pawl, and a series of dogs severally brought into engagement with the gear of each adding-wheel except the first, each by the retraction of the pawl actuating the next preceding wheel, substantially in the manner and for the purpose herein set forth. 10
3. The combination, with the train of adding-wheels, a corresponding series of master-wheels severally geared thereto, a series of oscillating pawls severally actuating said 15

master-wheels, and a series of springs severally actuating said pawls to produce automatically an independent movement of each pawl to move its appropriate adding-wheel, of a series of spring-actuated dogs severally mounted to engage and lock each adding-wheel, but normally disengaged therefrom by a spring, and a cam-disk moving with each pawl to enforce the action of the dog engaging the wheel next following that moved by said pawl, whereby said second wheel is locked by the dog until the pawl has finished its stroke and completed the movement of the first wheel, substantially in the manner and for the purpose herein set forth. 20

In witness whereof I have set my hand, this 13th day of January, 1890, in the presence of 25 two witnesses.

WILLIAM KOCH.
